UNITED STATES PATENT OFFICE.

SAMUEL HARDY, OF HOBOKEN, NEW JERSEY, ASSIGNOR TO A. G. SPALDING & BROS., OF NEW YORK, N. Y., A CORPORATION OF NEW JERSEY.

CENTER STRAP FOR TENNIS NETS.

Application filed July 10, 1922. Serial No. 574,020.

To all whom it may concern:

Be it known that I, SAMUEL HARDY, a citizen of the United States, residing at Hoboken, in the State of New Jersey, have 5 invented certain new and useful Improvements in Center Straps for Tennis Nets, of which the following is a specification, reference being had to the accompanying drawings, forming a part hereof.

10 This invention relates to a combination of elements for securing a tennis net at its mid-section and has for its principal object to provide devices which shall be of simple construction, effective in operation, convenient for installation and adjustment, and durable. The improved construction includes a hook at the lower end of the center strap which is swiveled in such manner as to permit the strap to revolve about the axis 15 of the shank without twisting. It has been found in known constructions that the anchorage for center straps has been unsatisfactory in that it has not provided for convenient installation and has not been of such 20 character as to adapt itself to twisting of the strap. The improved hook employed in the anchorage, in the present case, includes, in the preferred form, a snaffle which facilitates attachment and detachment from the 25 anchor and positively holds the strap against accidental disengagement. Another feature of the invention is the association with a hook of the character described of a center strap which comprises an endless band adjustable through a buckle and extending 30 through a slot in the base of the hook. Free sliding movement of the strap in this base and free adaptation of the strap to the net without twisting, by virtue of the swiveled 35 shank of the retaining hook increases the life of the center strap materially since it protects it against undue strains and stresses and insures its constant change of position 40 with respect to the top of the net where the greatest wear is ordinarily encountered.

The preferred embodiment of the invention will be described in detail with reference to the accompanying drawings wherein: Figure 1 is a view in elevation of a section of a tennis net equipped with the improved strap.

Figure 2 is a detailed view on an enlarged

scale of a portion of the center strap and its retaining hook.

Figure 3 is a view in side elevation of the 55 strap shown in Figure 2.

The lawn tennis net *a* may be secured at its side edges by any suitable means and retained in place adjacent to its mid-section by the improved center strap *b*. This center 60 strap comprises an endless strip of fabric such as canvas, one end of which carries a suitable buckle *c* adapted to be engaged with the free end *b'* of the strap whereby the length thereof may be adjusted conveniently. 65 A finger-piece *c'* on the buckle *c* facilitates this adjustment in accordance with usual practice where buckles or the equivalent are employed. The strap *b* passes through a slotted base *d* in which is swiveled a vertical 70 shank *e* for a hook *e'* which may be closed by a spring pressed snaffle *e*². It will be observed that the axis of the shank *e* is vertical and substantially coincident with the median line of the vertical strap *b* when in position. 75 The hook *e'* may be engaged with any suitable anchor illustrated for convenience as a horizontal pin *f* supported in an anchor *g*. The invention is not concerned with the character of the anchor.

80 From the description it will be evident that the strap *b* being formed as an endless loop passing through the slotted base *d* is free to move longitudinally therein and so change its bearing section on the upper edge 85 of the tennis net *a*. This is important inasmuch as such straps are subject to hardest wear at this point. Further, the buckle *c* affords a most ready means of adjusting the effective length of the loop formed by the 90 strap *b* so that the latter may under changing conditions of weather which might cause stretching or shrinking, always be pulled so as to hold the upper edge of the tennis net at the regulation distance from the surface 95 of the ground. Again, the swiveled shank *e* permits twisting of the strap to any degree necessary to insure ready conformation to distortion in the net. The result is that the strap is not subjected to undue stresses or strains such as might be brought about by twisting. The snaffle *e*² affords a positive closure for the hook *e'* so that it may be positively engaged with the anchor and all

of the parts held in desired relation against accidental disengagement.

What I claim is:

In combination with the center strap for a tennis net formed as an endless band, a buckle to secure the free ends of the bands adjustably together, a hook having a slotted base through which the strap is loosely passed, a vertical shank for the hook swivel-

ed in the base with its axis substantially in line with the median line of the strap to permit the strap to revolve about its axis without twisting, and a snaffle to close the hook.

This specification signed this 5 day of 15 July A. D. 1922.

SAMUEL HARDY.
